UNITED STATES PATENT OFFICE.

HENRY L. FORHAN, OF PORTLAND, MAINE.

REVOLVER FOR PROCESSING CANNED GOODS.

No. 900,064.

Specification of Letters Patent.

Patented Sept. 29, 1908.

Original application filed February 13, 1907, Serial No. 357,178. Divided and this application filed January 17, 1908.
Serial No. 411,921.

To all whom it may concern:

Be it known that I, HENRY L. FORHAN, a citizen of the United States, residing at Portland, in the county of Cumberland and State 5 of Maine, have invented an Improved Revolver for Processing Canned Goods; and I hereby declare that the following is a full, clear, and exact description of the invention, which will enable others skilled in the art to 10 which it appertains to make and use the same.

My invention relates to revolvers for processing canned goods and this application is a division of my former application, No. 15 357,178, filed February 13, 1907 upon which Letters Patent No. 885332 were issued April 21, 1908.

It is the purpose of my invention to provide a container or revolver for holding hermetically sealed cans while they are being processed in the retort, said container being so constructed and operated as to cause each can to revolve during the process and at some point during said revolutions of the 25 cans, to receive a sudden check by which the revolution of the cans is arrested thus agitating the contents.

In the drawing: Figure 1 is a vertical transverse section of the container or revolver showing one of the pans therein; Fig. 1* is a side elevation of the retort with parts broken away; Fig. 2 is a detail showing the recess in the rear end of the retort for the admission of the shaft; Fig. 3 is a detail showing the rear wall of the revolver in cross section and a portion of the shaft therein; Fig. 4 is a side elevation showing the rear end of the retort and revolver; Fig. 5 is an end view of the ordinary retort with the door removed, 40 and the revolver therein; Fig. 6 is a detail showing the rollers disposed from side to side of the track.

The retort *a* is of the ordinary construction, see Figs. 4 and 5. It is provided at the 45 side of the front end with the ordinary swinging clamps *b*, *b* by which the door is clamped in position. At the rear end the retort is also provided with a bracket *c* which supports in a proper journal the shaft *d* which enters the 50 rear end of the retort through a suitable air tight passage and terminates in a square or rectangular head. This shaft *d* may be provided, as shown in Fig. 4, with a gear *e* intermeshing with the gear *f* upon a shaft hay-

ing a pulley *g* which may be belted to the 55 main or other shaft, or various other means for imparting power to the shaft may be used. The bottom of the retort should be provided at either side with a track or guide *p*, *p*, see Figs. 5 and 6. *f* is a hollow cylinder 60 of metal, the ends and sides of which I prefer to perforate with small holes *g*, *g*. The rear end of the cylinder is centrally provided with a square or rectangular opening *h* for the reception of the head or end of the shaft 65 *d*, see Fig. 3. The front of this cylinder has a removable cap *l* which may be secured, when desired, to the cylinder by clamps, locks or other fastening devices. For the reception and holding of the cans, I provide 70 pans *k*, *k*, the diameter of which are slightly less than the diameter of the cylinder *f*. Within the pans, I provide a partition *h* in the form of an involute circle or spiral, see 75 Fig. 1. The partition extends from the central stud spirally to the wall of the pan. The space between the various parts of the spiral or partition is slightly greater than the diameter of the cans: see Fig. 1. The depth of the retaining side of the pan and of the 80 partition *h* which forms the involute circle is slightly in excess of the height of the cans to be operated on.

The operation of the device is as follows: The pan *k* is placed upon its side and nearly 85 but never quite filled with cans as shown in Fig. 1. When the cans have thus been placed in the pans, the pans are placed in the cylinder *f* until it is filled. The cap of the cylinder is now placed in position and secured and 90 the cylinder placed upon the specially constructed truck *m*, see Fig. 5, or the cylinder may be filled upon said truck. This truck is provided with wheels at each corner adapted to run in the tracks *p*, *p*, and is also provided 95 with two rollers *o*, *o*, one on each side, see Fig. 5, the axes of these rollers being at right angles with the axes of the wheels *n*, *n*. I do not, however, confine myself to a single roller at each side of the truck as their number 100 may be increased, so that the cylinder rests upon a succession of rollers extending from side to side of the truck diminishing gradually in diameter towards the center, see Fig. 6. The truck is now rolled into the retort 105 upon the tracks *p*, *p*, see Fig. 5, and when the cylinder is completely within the retort, the aperture *h* in the rear of the cylinder

receives the end of the shaft *d*. The door 11 is now closed in the ordinary manner and clamped and steam admitted to the retort through the pipe 5, see Fig. 4. Power is applied to the shaft *d* which causes the cylinder *f* to revolve and the cylinder *f* is revolved a number of revolutions, allowing each can to revolve a certain distance, which is equal to the space between the partitions not occupied by cans, when the revolutions of the cans cease. The rotation of the shaft *d* is then reversed causing the cans to revolve in the opposite direction with a like agitation when rotation again ceases preparatory to revolution in reverse direction.

The cooling of the cans may be effected before removal from the retort, cold water being admitted through the pipe 5 and the cylinder revolved in the same manner as while the cans are being processed or, if preferred, the cylinder *f* may be removed from the retort, after the processing is accomplished and placed in a like retort to which cold water may be admitted and the cylinder *f* then revolved as during the processing of the cans.

The advantage and improvement over the device covered by my said Letters Patent, No. 885,332, hereinbefore referred to, in which the partitions are made circular arising from disposing the partitions spirally from the center of the partitions to their outward wall as in the present application is found in greatly increased number of cans which may be placed in pans of the same diameter. In the construction shown in said Letters Patent a space equivalent to two or more cans must be left in each compartment formed by the circular partitions and the transverse partitions, whereas in the present application

a space equivalent to two or three cans only need be left in the entire pan.

What I claim is:

1. In an apparatus for processing canned goods, a retort, a series of pans, each provided with a spiral partition extending from the center of the pan to the wall thereof, a container adapted to receive and hold said pans, and means for revolving said container first in one direction and then in the other 45 within said retort, substantially as described. 50

2. In an apparatus for processing canned goods, a retort, a series of pans, each provided with a spiral partition, a container with perforated walls, and means for revolving 55 said container first in one direction and then in the other within said retort, substantially as described.

3. In an apparatus for processing canned goods the combination of a retort, a horizontal container situated within the retort, removable pans adapted to be supported upon their sides within said container, each of said pans provided with a spiral partition extending from the center of the pan to the wall 60 thereof forming a continuous canal for the reception of cans, said canal being of substantially the same width as said cans, and means for revolving said container first in one direction and then in the other, whereby 70 said cans are revolved in opposite directions and agitated.

In testimony, that I claim the foregoing as my invention I have hereunto set my hand this fourteenth day of January, A. D. 1908. 75

HENRY L. FORHAN.

Signed in presence of—

GEO. E. BIRD,
JAMES R. PARSONS.
